UNITED STATES PATENT OFFICE.

HERMON L. ENSIGN, OF CHICAGO, ILLINOIS.

IMPROVEMENT IN HYDRAULIC ELEVATORS.

Specification forming part of Letters Patent No. 123,161, dated January 30, 1872.

SPECIFICATION.

I, HERMON L. ENSIGN, of Chicago, in the county of Cook and State of Illinois, have invented an Improvement in Hydraulic Elevators, of which the following is a specification:

The nature of the present invention consists in the novel construction and arrangement of our elevating-tank and supply-tanks, whereby the elevating-tank is made to receive a suitable quantity of water to elevate the platform; and in the novel construction and combination of a ball-governor and brake, which are arranged to automatically control the movement of the platform, as the whole is hereinafter fully described and shown.

In the drawing, Figure 1 is a side elevation of the drum, brake, and governor; Fig. 2, a sectional elevation of the elevator as it is in position in a building; Fig. 3, an enlarged broken sectional elevation of the elevating-tank and one of the supply-tanks, showing the novel construction of the valves by means of which the elevating-tank is filled.

E represents the vertical wall of a building, and F G H I the joists forming the floors of the several stories. D represents an ordinary elevating-platform, which is held in position in its vertical movement by means of guides K K', Fig. 2, and which is raised and lowered by means of a rope, b, passing over a drum, R. The opposite end of the rope b from that end fastened to the platform D is fastened to an elevating-tank, J, which is supplied with water from tanks A B C, as hereinafter shown, and which is held in proper position in its vertical movement by means of the guide K'. The lower ends of the tanks A B C, adjoining the elevating-tank J, are provided with valve-doors m, Fig. 3, which are hung to the tanks at k, and swing inside of them, and which are provided with projecting nibs f, extending outwardly to the valves x in the elevating-tank J. This valve x is hung to the tank at h, and is arranged to swing outwardly from it, and it is held shut as against the pressure in the tank J by means of a rubber strap, e, Fig. 3, which is fastened to the valve and to the opposite side of the tank from the valve. The device for opening the valves m x consists of a lever, f', which is pivoted to the tank J at n, and which is operated by a cord, c, passing over

the same drum R that the rope b passes; said cord c projecting down to the platform D, so as to be in reach of the operator. This arrangement is such that, when the cord c is drawn upon, the short end of the lever f' will force the valve x open, and, consequently, force the valve m inwardly, so that water will readily flow from either of the tanks A B C into the tank J. The devices for braking or controlling the motion of the drum R and movement of the platform D are as follows: A bevel-gear wheel, P, is fastened to the same shaft, Q, that the drum R is, and, when rotated with the drum, drives a bevel-pinion, O. This pinion supports two or more standards, Z, Fig. 1, to the top ends of which is fixed a sleeve, d, of suitable strength to support the levers v v of a ball-governor, which are pivoted to it. W W represent connecting-rods, which are jointed to the upper ends of the levers v v, and to an upper sleeve, x', said sleeve bearing on a shoulder formed on the brake-rod U. This rod has bearings in an upper frame-piece, y, and in a lower frame-piece, S, and to its lower end is fastened a curved spring-brake, T, Figs. 1 and 2, which is formed on a quicker curve than the brake-wheel N, on which it operates, so that when the rod forces the spring T down the latter will have a friction-surface of nearly its entire length. The operation of the governor is such that when the balls are thrown outwardly by the increased motion of the pinion O the connecting-rods W will draw the sleeve x' downwardly, and, consequently, cause the rod U to move downwardly and set the brake T to the brake-wheel N, inasmuch as the rod U only has a vertical movement, while the governor and sleeves rotate around it. The rod U also performs the function of holding the pinion O in position to rotate and carry the governor by means of the aforesaid standards Z. At the bottom of the tank J is a valve, r, which is operated by a cord, a, and used to discharge the water of tank J into any of the tanks A B C by means of a curved pipe, g, said cord coming, after passing over the drum R, down to within reach of the operator standing on platform D.

The operation is simple and as follows: The platform D in Fig. 2 is shown at the bottom of the lower story. Now, when any weight thereon is to be raised, sufficient water from

tank A is to be let into tank J to elevate the platform and its load thereon, the valves closing automatically when the cord c is loosened, and the tank J begins to move down. Any of the tanks A B C can be used to supply tank J, according to its position, and the lower tanks will receive the water from tank J when it has too much therein to elevate a light load. In practice I intend to use any suitable stopping device, so that the platform may be held in any given position, and so that the valves m α may be held opposite to each other when the tank J is being filled. By this means a simple, cheap, and safe elevator is provided, saving the cost of an engine and liability of fire therefrom, while, at the same time, hose may be attached to the tank to use in case of fire in oth-

er parts of a building. The elevator is adapted to all places where a sufficient supply of water can be had at a suitable height in a building.

I claim and desire to secure by Letters Patent of the United States—

1. The combination of the platform D, elevating-tank J, one or more supply-tanks, A B C, brake T U, and governor v W x' d Z, as set forth.

2. The combination of valves m α r , nibs f, tanks A B C, platform D, rope b, rubber strap e, and governor, as described and set forth.

HERMON L. ENSIGN.
